APPARATUS FOR AND METHOD OF RE-CORDING SOUND ON FILM

Glenn L. Dimmick, Erlton, N. J., assignor to
Radio Corporation of America, a corporation
of Delaware

Application November 28, 1936, Serial No. 113,128

3 Claims. (Cl. 179—100.3)

This invention relates to a new and improved apparatus for and method of recording sound on film.

The invention relates particularly to the production of variable density sound records by what is commonly referred to as the "penumbra" method, and involves the application of that method to the making of push-pull variable density sound records. In addition to this, it involves 5 the production of variable density sound records with ground noise reduction and variable density sound records wherein each half of the sound track includes only substantially one-half of the sound wave, the other half of the sound wave 10 appearing on the other sound track, and there being no record on the sound track between the individual half waves.

One object of the invention is to provide a novel apparatus for recording variable density 20 sound records.

Another object of the invention is to provide a novel apparatus for producing variable density push-pull sound records.

Another object of the invention is to provide 25 a novel method of producing variable density push-pull sound records.

Another object of the invention is to provide a novel optical system for sound recording.

Another object of the invention is to provide 30 a novel means for reducing ground noise in variable density sound records.

Another object of the invention is to provide a variable density sound record in which ground noise reduction is inherent.

35 Other and incidental objects of my invention will be apparent to those skilled in the art from a reading of the following specification and an inspection of the accompanying drawings, in which

40 Figure 1 shows an apparatus for making variable density sound records by the penumbra method, which is somewhat similar to the apparatus described and claimed in my copending application Serial No. 745,793, filed September 27, 45 1934,

Figure 2 shows my improved optical system for making push-pull sound records.

Figure 3 shows the type of sound record produced by the aperture of Figure 2,

50 Figure 4 shows an aperture which may be substituted for the aperture shown in Figure 2,

Figure 5 shows the illumination on the slit plate which is produced by the aperture of Figure 4,

55 Figure 6 shows the type of sound record produced by the aperture shown in Figure 4, and

Figure 7 shows the double ground noise reduction shutter which may be used in conjunction with the aperture in Figure 2.

In the apparatus shown in Fig. 1, the usual exciter lamp is indicated 10, the light from which passes through a condenser lens 11 to a rectangular aperture 12. From the aperture the light beam passes the penumbra mask 13 and goes through the convex spherical lens 14 to the galvanometer mirror 15. The condenser lens 11 and 10 the lens 14 together serve to direct an image of the filament of the exciter lamp 10 onto the galvanometer mirror 15.

The positive spherical lens 16, in cooperation 15 with the lens 14, focuses an image of the rectangular aperture 12 upon the slit plate 17. The mask 13 cuts off a portion of the light at one side of the beam and thereby causes the image 12' of the aperture 12 to be graduated in brightness from full intensity at one edge to practically zero illumination at the other edge, as described and claimed in my aforesaid application.

When the mirror 15 is vibrated about an axis more or less parallel to the slit 18 in the plate 17, the rectangular image 12' is caused to move 25 across the slit and thereby transmit a greater or less amount of light through the slit. An image of the slit 18 is formed upon the film F by the objective lens 19, which may be of the type of compound lens usually employed as a microscope objective, forming an image 18' on the film. 30 It will be apparent that when the mirror 15 is actuated in accordance with sound waves, the brightness of the image 18' will change to correspond, and as the film is moved longitudinally 35 a sound record will be produced varying in density in accordance with the sound waves.

In Fig. 2 the same general arrangement of elements is provided as in Fig. 1, and elements which are the same in structure and operation 40 carry the same reference numerals in both figures. In this form of the invention, however, a plate 23, having two apertures 24 and 25, is substituted for the penumbra mask 13. Each of these apertures operates in the same manner on 45 its half of the beam as the mask 13 operates on the entire beam. One aperture shades the lower half of the beam on its side of the axis and the other aperture shades the upper half of the beam on its side of the axis.

Instead of the lens 14, a pair of lenses 26 and 50 27 are provided, 26 being a positive spherical lens and 27 being a positive cylindrical lens with its axle vertical. These lenses, together with the lens 11, as in Fig. 1, focus light from the lamp 10 55

- onto the galvanometer mirror 15, and an appropriate image of the mask 23 is focused by the lenses 26, 27, 16 on the slit plate 17. However, in this form of the invention it is necessary that the vertical edges of the apertures 24 and 25 be sharply defined, in order to prevent overlapping of the two halves of the sound record, while at the same time the two effective horizontal edges of the apertures 24 and 25 must not be sharply focused, in order that they may produce a uniformly shaded image. The lenses 26, 27 and 16 are, therefore, so chosen as to focal length that a sharp image will be formed on the plate 17 of the vertical edges of the apertures 24 and 25.
- 15 Due to the fact that the cylindrical lens 27 is effective in the horizontal plane only, the system will not form a sharp image of the horizontal edges of the apertures, and therefore images 24' and 25' will be produced having sharply defined vertical edges and vertically shading gradually from maximum brightness at the outermost edges to a minimum brightness at their inner edges. Images of the two portions of the slit will be formed on the film F by the lens 19, as in Fig. 1, when the mirror 15 is oscillated about its axis, and the two shadows will traverse the slit and thereby produce oppositely modulated sound tracks on each side of the median line, as shown in Fig. 3.
- 30 If the aperture plate 33, shown in Fig. 4, be substituted for the aperture plate 23 in Fig. 2, then the shadows on the slit plate 17 will take on the appearance shown in Fig. 5, where the rectangular spots of light are of the minimum brightness at the slit 18 and maximum brightness at their outer edges. It will be apparent from this that when the mirror is actuated, one of these rectangular spots will move away from the slit 18, producing no exposure whatever, while the other spot will move across the slit, producing an exposure on its half of the sound track of gradually increasing density.

On the opposite movement of the galvanometer mirror, the reverse will occur, and there will thus be produced a sound track having alternate edges of the sound waves on opposite sides of the median line, with almost no exposure between the halves, as shown in Fig. 6. This type of sound track, where each half sound track operates only during one-half of the cycle, is generally referred to as Class B, as distinguished from the type of sound track before described where equal and opposite impressions occur at all times on each half sound track, which is generally referred to 55 as Class A. It will be apparent that by properly

choosing the size and placing of the apertures in the aperture plate, I may produce a sound track which partakes of the characteristics of both the Class A and Class B sound tracks, i. e., at low modulations equal records are produced with the two halves, while at high modulations one-half of the sound track will reach zero exposure before the other half reaches its maximum exposure. This type of track is referred to as Class A-B, or as Class A'.

10 In order to produce a Class A sound track with a minimum of ground noise, I may add the shutters shown in Fig. 7 to the aperture 23 in Fig. 2, or may substitute such shutters for that aperture. These shutters 43 and 44 are mounted on appropriately pivoted arms 45 and 46, which are adapted to be actuated by the magnets 47 and 48. These magnets may be connected either in series, as shown, or in parallel, and the shutters may be provided with such guides, stops and springs as may be necessary. The magnets 47 and 48 are connected to an appropriate ground noise reduction amplifier, such, for example, as shown in McDowell Patent 1,855,197, and are thereby caused to move in opposite directions in accordance 25 with the envelope of the sound waves. Thus at low sound intensities the shutters may overlap each other considerably and produce a minimum exposure on the film, while at the higher sound intensities they gradually withdraw toward the 30 maximum position, in which they are shown, in accordance with the amplitude of the modulation, thereby producing a sound record having an average exposure corresponding to the amplitude 35 of the sound waves and having this exposure modulated in accordance with the sound waves.

I claim as my invention:

1. Apparatus of the class described comprising means for directing a beam of light in the form of a fine line upon a record film, means for vibrating said beam of light in accordance with modulation to be recorded, a slit in the path of said beam of light between said vibrating means and said film, and opposed masking means in the path of said beam of light producing opposed penumbras upon said slit, whereby separate portions of said beam are varied oppositely in brightness by actuation of said vibrating means.

2. Apparatus as defined in claim 1 wherein the masks are so arranged that only one-half of the 50 said line is illuminated at one time.

3. Apparatus as defined in claim 1 wherein the masks are movable in accordance with the envelope of the sound waves.

GLENN L. DIMMICK. 55
